SwitzerlandApplication November 23, 1934, Serial No. 754,402
In Switzerland December 4, 1933

15 Claims. (Cl. 123—27)

The invention relates to an internal combustion engine in which the fuel is preheated. As is well known in internal combustion engines the combustion of heavy oils, i. e. fuel containing asphalt, is accompanied with great difficulties, especially when the fuel is injected without air.

In an internal combustion engine according to the present invention these difficulties are overcome by heating the fuel, before it is led to the fuel pump, under a pressure generated by means of a delivery device or a pressure medium, thus avoiding any evaporating of the fuel. Preferably the pressure is adjustable and higher than the evaporating pressure of the water contained in the fuel, corresponding to the preheating temperature. Also the preheating temperature chosen may be such that the preheated fuel has a viscosity at the maximum of 8° Engler. Further the fuel pump may be provided with a heating jacket through which the surplus of preheated fuel is passed.

Two examples of construction according to the invention are shown diagrammatically in the accompanying drawing.

Fig. 1 shows an internal combustion engine with a device for preheating the fuel and putting it under pressure before it is admitted into the fuel pump.

Fig. 2 is a variant of Fig. 1.

The internal combustion engine 1 in Fig. 1 has a fuel pump 2, the drive of which is for simplicity's sake not further illustrated. The fuel pump 2 delivers the fuel through the pipe 4 to the injection valve 5 in the cylinder covers 7. From the tank 8 fuel is drawn in through the suction pipe 9 by the pump 10 and delivered through the delivery pipe 11 into the delivery tank 12. From the delivery tank 12 the pipe 13 leads to the stop valve 14, to which the suction pipe 16 of the fuel pump 2 is connected. The pipe 11 is surrounded by a heating jacket 17, to which the heated cooling water flows from the cylinder cover 1 through the pipe 18; through the pipe 19 it is led away. Within the widening 20 of the exhaust gas pipe 21, the pipe 13 is divided and the two pipes 22 are provided with ribs in order to ensure good heat transmission. From the pipe 13 the pipe 23 with the regulating valve 24 branches off to the tank 8. By means of the pipe 26, which can be shut off by means of the valve 25, compressed air, which may be taken for example from the starting-air bottles, can be introduced into the tank 12.

The method of operation is the following. The fuel in tank 8 is heavy oil, and a lighter oil is

injected for starting the internal combustion engine 1. Therefore the flow of heavy oil to the fuel pump 2 is first of all shut off by means of the fuel valve 14, and the valve 27 is opened, thus allowing light oil to be led from the tank 5 28 to the pipe 30 to the fuel pump 2. Meanwhile the heavy oil is put under pressure by means of the pump 10, before it is introduced into the fuel pump 2, and is preheated by the hot cooling water in the heating jacket 17 and also by exhaust gases in the parts 22 of the pipe 13 provided with ribs. The heating of the fuel in pipe 11 can be regulated by adjusting the quantity of cooling water by means of the stop cock 31. When the heavy oil has been sufficiently heated, 15 the valve 27 is closed and the valve 14 opened so that the fuel pump 2 from that moment delivers heavy oil.

In order to regulate the temperature of the heavy oil in still another manner, the quantity 20 of fuel delivered by the pump 10 is regulated before the fuel pump 2 by means of the regulating valve 24, the surplus of fuel flowing back through pipe 23 into the tank 8. The pressure 25 of the fuel before the fuel pump 2 can be regulated not only by means of the pump 10, for example by altering its speed and the quantity flowing through the overflow valve 24, but also by opening the valve 25 and the compressed air pipe 26 on the tank 12. This causes a constant 30 pressure to be exerted on the fuel in the tank 12 independently of the fuel consumption. This additional pressure from the compressed air piping of the internal combustion engine 1 is not required in all cases. The drive of the fuel 35 pump 2 in Fig. 1 is shown in Fig. 2.

In Fig. 2 the tank 33 itself is surrounded with a jacket 34, whereby the warmed cooling water coming from the cylinder cover through the pipe 18, which is provided with the regulating valve 40 31, enters into the jacket 34 and flows away through the pipe 35. The fuel is withdrawn from the tank 33 by the pump 37 and arrives at the suction valve 44 of the fuel pump 2 through the pipe 38 with the piece 39 provided with ribs in 45 the widening 40 of the exhaust pipe 21 through the valve 41, the pipe 42 and the suction pipe 43. Branches 46, 47 are provided before and after the valve 41 and are fitted with closing members 48, 49 and furnished with ribs within the widening 50 of the exhaust pipe. The two branches 46, 47 pass over to the bypass pipe 51 which is shut off from the pipe 42 by means of the valve 52.

The pipe 42 is separated from the suction pipe 43 by the three-way cock 53. As a third pipe, the 55

pipe 55 fitted with the regulating valve 54 branches off and is connected by means of the three-way cock 57 to the pipes 58 and 59. The pipe 58 leads to the jacket 60 of the fuel pump 2, from which also the pipe 59 branches off. The plunger 62 is operated by the cam 63 which is driven from the crankshaft 64.

Starting is also effected by shutting off the suction pipe 43 from the pipe 42 by means of the three-way cock 53 and leading light oil from the tank 28 to the fuel pump 2, whilst the pump 37 circulates the fuel over the heating elements 39, 46, and 47 in order to bring it to the required preheated temperature. When putting all the ribbed pipes 39, 46, and 47 into operation, the valves 41 and 52 are closed and the valves 43 and 49 opened, so that the fuel arrives first of all in the ribbed pipe 39, and then in the ribbed pipe 46 and finally in the ribbed pipe 47 and from there through the valve 49 to the pipe 42, after which it returns through the three-way cock 53 and 57, which are then in position II, through the pipes 59 back again to the fuel tank 33.

If, however, the heated heavy oil is to flow back through the jacket 60 of the fuel pump 2, the three-way cock 57 is brought into the position I, so that the heated fuel flows through the jacket 60 to pipe 59.

For regulating the heat taken from the exhaust gases, the ribbed pipes 47 and 46 can be put out of operation, whereby, if two ribbed pipes are put into operation, the fuel flows through the ribbed pipe 39 with the valve 48 open and through the ribbed pipe 46 with the valve 41 closed, arriving at pipe 42 through the bypass 51 with valve 52 open and valve 49 closed. If only one ribbed pipe is put out of operation the valves 48, 49, and 52 remain closed and the valve 41 open.

The ribbed pipes 46, 47 are emptied when out of operation, in order to prevent evaporating or coking of the fuel remaining in them. For this purpose the cocks 65, 66 and 67 are used. When putting the ribbed tube 47 out of operation, the three-way cock 67 is turned from position III into position IV, so that the ribbed pipe 47 is shut off from the pipe 51 but connected with the pipe 69 which leads to the fuel tank 8. After the cock 65 is turned from position VI to position VII, in order that the connection 70 on the compressed-air pipe is connected with the ribbed tube 47 and compressed air can empty the pipe 47. If the pipe 46 is put out of operation in addition to the pipe 47, the three-way cock 67 is turned into position V with cocks 52, 49, and 48 closed, and then the cock 46 is also turned from position VI into position VII. If a ribbed pipe which has been emptied is again put into circuit, it is first of all filled with fuel by bringing the cock 65 or the cocks 65 and 66 into position VIII so that the ribbed pipes are given directly a free outlet for the air with the valves 49 and 48 still closed. The cocks 65, 66 are brought back into position VI as soon as the fuel issues from the open overflows 71.

As soon as the fuel is sufficiently warm, cock 27 is closed and the three-way cock 53 is brought back into position I, so that the heavy oil, which has been put under pressure by means of the pump 10 and preheated in tank 33 and in exhaust pipe 21, is now led to the fuel pump 2, and thereby delivered into the injection valve 5. This valve works automatically in a manner known in itself, in that the nozzle is closed by means of a needle loaded with a spring. During injection, the needle is raised under the influence of the fuel

pressure. Illustration of this is omitted for the sake of simplicity. The needle could also be controlled automatically from the shaft of the cam 63. By turning the three-way cock 57 into position I, the fuel pump 2 is preheated also when injecting heavy oil, and the quantity of oil circulated can be regulated by means of the valve 54.

It may easily happen that some water is contained in the fuel. Consequently, in known devices for injecting fuel, the water vapour and the gas bubbles are led away from the heated fuel, since preheating with the known devices occurs only under natural pressure, i.e. exclusively under the influence of gravity. The evaporating pressure of the water contained in the fuel corresponding to the preheating temperature, is already so high in the case of preheating temperatures of 70° C. and more, that when in order to avoid steam bubbles in the fuel, which adversely influences the delivery of the injection of the fuel, a pressure higher than this evaporating pressure is adopted, this pressure can no longer be a natural pressure but must be caused artificially by means of a delivery device or a pressure medium. The preheating temperature of the fuel is also dependent on the viscous properties of the fuel. The preheating temperature for heavy oil should be at least so high that the preheated fuel has a viscosity of at the most 8° Engler in order to obtain injection which is at least fairly good.

The advantage of circulating the fuel consists in that the preheating temperature can be more exactly regulated, and this regulation is in certain respects independent of the exhaust gas temperature.

When regulating the artificial pressure on the fuel before the fuel pump by means of the introduction of compressed air to tank 12 or 33, the preheating temperature can be regulated either by setting the closing member 24 or 54 by hand, or maintained at a constant value by means of thermostats. This necessitates a double regulation of the pressure and of the temperature.

It is also possible, however, to fit a regulating valve 72 in the pipe 9, as shown in Fig. 1, whereby the gearwheel pump 10 delivers a constant quantity of fuel. The pressure in the whole system is kept constant in that the regulating valve 24 is at the same time designed as an automatic pressure regulating valve which opens further in consequence of the rise in pressure and leads back through pipe 23 to tank 8 as much fuel as is necessary to lower the pressure to the predetermined value. In this case the valve 25 is closed. Finally, the artificial pressure of the fuel can also be kept constant and the preheating temperature altered in accordance with the load, in that the system is set to give a sufficient preheating of the fuel at the lowest load and the artificial pressure is so high that evaporation of the fuel at the maximum load is prevented. In this case the regulating valve 24 is open only for an initial circulation of the fuel, but is closed in service, as is also the valve 25.

In certain cases the connection 26 of the tank 12 to the compressed air system of the internal combustion engine 1 may be entirely omitted and the constant artificial pressure of the fuel is maintained through the bypass pipes 13 with the pressure regulating valve 74, in that the regulating valve 74 is set to a predetermined pressure and leads any surplus back to the tank 8. The regulating valves may be adjustable, for example in dependence on the kind of fuel.

Further, circulating the fuel by means of a pump 37, whereby the fuel flows back into the pressure tank, gives the advantage that losses of heat and pressure in the fuel are avoided in comparison with the method of leading the fuel into a storage tank which is not under pressure. The adoption of an automatic or controlled injection valve has the advantage that the height of the preheating temperature is not limited by the conditions existing between fuel pump and working cylinder, in that in long pipes the formation of steam or gas bubbles between the two, and consequently a rather inaccurate injection, is avoided.

I claim:

- 15 1. In an internal combustion engine the combination of a pump for injecting liquid fuel into the engine cylinders, means for preheating the fuel prior to its delivery to said pump to a temperature at which vaporization of the more volatile constituents of the fuel would take place at atmospheric pressure, means for maintaining said fuel during preheating and its subsequent delivery to the fuel pump under a pressure sufficient to prevent vaporization of the more volatile constituents contained in said fuel.
- 20 2. In an internal combustion engine, the combination of a liquid fuel supply, a pump for injecting fuel into the engine cylinders, conduits for conducting fuel from said fuel supply to said injection pump, a pump for forcing fuel from said fuel supply to said injection pump, and means for preheating the fuel between said pumps to a temperature at which vaporization of the more volatile constituents of the fuel would take place at atmospheric pressure, the pump for forcing the fuel from the fuel supply to the injection pump exerting a force on the fuel sufficient to prevent vaporization of the more volatile constituents contained in the fuel.
- 25 3. A combination as set forth in claim 1 in which means are provided for varying the pressure on the fuel during preheating and delivery to the fuel pump.
- 30 4. A combination as set forth in claim 1 in which the pressure on the fuel during preheating and delivery to the fuel pump is greater than the evaporating pressure of water contained in the fuel.
- 35 5. A combination as set forth in claim 1 in which the fuel is preheated so that it has a viscosity at the maximum of 8° Engler.
- 40 6. A combination as set forth in claim 1 in which a circulatory system is provided for the preheated fuel.
- 45 55 7. A combination as set forth in claim 1 in

which valve-controlled conduits are provided for bypassing fuel from the engine cylinders when desired.

8. A combination as set forth in claim 1 in which the fuel pump is provided with a heating jacket and in which means are provided for passing a portion of the preheated fuel through said jacket.

9. A combination as set forth in claim 1 in which valve-controlled conduits are provided for bypassing fuel from the fuel pump when starting the engine, and in which means are provided for introducing a starting fuel to the fuel pump when the main fuel supply is bypassed therefrom.

10. A combination as set forth in claim 1 in which exhaust gases from the engine are utilized as the means for preheating the fuel.

11. A combination as set forth in claim 1 in which the exhaust gases passing through the exhaust conduit are utilized as a source of heat for preheating the fuel and in which a plurality of passages for fuel are provided in said exhaust conduit and in which means are provided for bypassing at least one of the passages for the fuel located in said exhaust conduit.

12. A combination as set forth in claim 1 in which the exhaust gases passing through the exhaust conduit are utilized as a source of heat for preheating the fuel and in which a plurality of passages for fuel are provided in said exhaust conduit and in which means are provided for bypassing at least one of the passages for the fuel located in said exhaust conduit, and in which means are provided for draining fuel from the fuel passages in the exhaust conduit which have been bypassed.

13. A combination as set forth in claim 2 in which a conduit is provided for bypassing fuel from the outlet side of the pump for forcing fuel from the fuel supply to the injection pump, and in which said bypassed conduit is provided with pressure-regulating means which maintains the fuel being forced from the fuel supply to the fuel injection pump under a predetermined pressure.

14. A combination as set forth in claim 1, in which the internal combustion engine is provided with a water-cooling jacket and in which cooling water from said jacket is utilized as the preheating means for the fuel.

15. A combination as set forth in claim 1 in which compressed air is utilized at least in part for maintaining fuel under pressure during preheating.
